UNITED STATES PATENT OFFICE

PIERRE ZUCCO, OF SAN FRANCISCO, CALIFORNIA

METHOD AND APPARATUS FOR FORMING PILES

Application filed August 29, 1930. Serial No. 478,746.

This invention relates to improvements in the formation of piles and more particularly to the type which are screw driven, as exemplified in the patent to Grimaud, #1,563,024, issued November 24, 1925.

The Grimaud patent, although proving an improvement in the art, is open to objections which my invention is designed to overcome. When it is attempted to sink the Grimaud pile, the rotary movement of the pile itself causes a torsional stress which serves to injure the interior of the pile and where the same is used in long lengths in hard ground, the pile is not at all satisfactory. For this reason the length of the pile is necessarily limited and is only suitable to be used under the most favorable circumstances.

The prime object of my invention is to produce a pile which may be sunk by means of a rotary movement imparted to the point or lower end of the pile without subjecting the same to extreme torsion. Another object is to provide a construction wherein the casing may be readily removed or lifted without disturbing the screw point. By having the casing secured to the screw point or head by quick detachable means, the same may be removed or lifted and at the same time during the boring process, the main stress will be directed to the head and any torsion that may result from the boring movement will not injure the pile, since that is formed after the boring movement is completed and is made possible due to the ability to remove the casing from the screw head.

Other objects will be disclosed in the specification and claims, forming a part of this application.

In the drawing:

Figure 1 is a side elevation in section.

Figure 2 is a side elevation in section showing the casing removed from the screw head.

Figure 3 is a side elevation in section of a modified form of construction.

Figure 4 is a section taken on line 4-4 of Figure 1.

Figure 5 is a side elevation of a locking device, and

Figure 6 is a section taken on line 6-6 of Figure 5.

Referring to the drawing in which like numerals indicate similar parts, numeral 7 designates a screw head which may be solid with apertures 8 extending therefrom, as shown in Figure 1, the apertures 8 being preferably formed in the helically shaped threads 9; the apertures 8 connecting with conduits 10, leading to a central opening 11; or the screw heads may be hollow, depending upon the nature of the work. Where the screw heads are solid, as shown in Figure 1, grout or liquid cement may be poured into the hollow screw head 7 so that the same will exude through the apertures 8 to form a solid base 9' around the screw head 7. This step of course is performed after the desired depth has been reached and the construction of the pile commenced. On the top of the screw head 7 is formed a key 12, preferably square in shape, which will fit into a socket 13 of corresponding shape, said socket 13 being screw threaded at 14 to the inner wall 15 of the casing 16. This socket 13 may be cast or otherwise formed as a part of the casing 16 but so as to have the various sections making up the casing 16 of uniform construction, it is desirable to merely have the socket 13 screw threaded to the casing 16.

Figure 1 is also shown with an outer casing or tube 17. Where the soil is very crumbly and soft, it may be desirable to have the outer casing 17 which is not secured to the screw head 7 and does not rotate, but due to the fact that the screw head 7 is larger in diameter than its upper portion, this casing 17 may be inserted as the screw head 7 is screwed into the ground. A plate 18 corresponding to a washer is placed freely around the inner casing 16 so that the bottom edge 19 of the outer casing 17 would contact therewith and prevent any undue friction as the screw head 7 is rotated. It is obvious that other quick detachable means than the one illustrated can be utilized and still be within the scope of this invention.

As actually used, the casing 16 will have fitted to its lower end the socket 13 and the socket in turn will be fitted over the key 12. The point of the screw head 7 will be directed to the support in which the pile is desired to

be sunk and the same will be rotated either by manual means or mechanical means through the turning of the casing 16 which in turn will rotate the screw head 7. As the casing is lowered, additional sections may be added on by means of couplings 18 in the usual manner. If the sides of the excavation have a tendency to crumble, the outer casing 17 will be lowered and built up as the work progresses. Upon the desired depth being reached, the casing 16 will be disconnected and gradually raised as the material to constitute the pile is fed in through the casing 16. The screw head 7 is left in the ground to form an anchor and as the casing 16 is raised, the pile is formed. Where the outer casing 17 is used, this will form the outer wall of the pile and will become integrally connected to the screw head by means of the cement or other material. It is obvious that reinforcing material such as iron rods or wire may be utilized in the construction of such pile. The raising of the inner casing 16 will continue until the entire pile has been formed.

In the modified form of construction, as shown in Figure 3, it may be desirous of pre-casting or preforming sections of the pile and in such a casing, the screw head 7 is made with an additional length in the form of a shank 19. A key 12 is formed at the base of the shank 19 similar to the key shown in Figures 1 and 2 and a socket 13 is formed in the casing 16 in the same manner as in the Figures 1 and 2. As the casing 16 is lowered, additional preformed sections of the pile will be placed within the casing 16 and secured in position by cement or other means. Since the preformed sections 20 are spaced from the casing 16, it is possible to position these sections as the pile is driven, since the torsion that would naturally result is absorbed by the casing 16. However, this type of pile may be set in the usual manner after the drilling has been completed and the screw head 7 has assumed its final position. The outside casing 17 may likewise be utilized in this construction. Instead of the usual coupling 18, as shown in Figures 1 and 2, a quick detachable means 21 is utilized to connect the sections 22 of casing 16.

Having described my invention, what I claim new and novel is:

1. The method of forming a pile consisting in forcing a head having a passage extending therethrough and a detachable hollow casing into the ground, pouring cementitious material through said casing and head to form an anchor for said head and lifting said casing from said head as the pile is formed.

2. Method of forming a pile consisting in rotating a screw head having a passage formed therethrough and a detachable hollow casing into the ground, pouring cementitious

material through said casing and head to form an anchor for said head, detaching said casing from said head and lifting said casing as said cementitious material is poured to form the pile portion.

3. Apparatus for forming piles comprising a screwthreaded boring member having a channel axially extending therethrough, and having openings formed on the outer periphery of said member connected to said channel, a casing detachably connected to said boring member adapted to receive building material and direct same into said channel and openings on the outer periphery, said boring member forming an anchor for said pile, said building material adapted to surround the said boring member.

4. Apparatus for forming piles comprising a screwthreaded boring member having a channel axially extending therethrough and having openings formed on the outer periphery of said member connected to said channel, a casing connected to said boring member adapted to receive building material and direct same into said channel and openings on the outer periphery, said boring member forming an anchor for said pile, said building material adapted to surround said boring member.

In testimony whereof I affix my signature. 95
PIERRE ZUCCO.
